UNITED STATES PATENT OFFICE.

ALLEN E. J. LUCKHURST, OF RIDGEWOOD, NEW JERSEY.

FLEXIBLE BOAT-LAUNCHING DEVICE.

1,205,762.

Specification of Letters Patent. Patented Nov. 21, 1916.

Application filed June 1, 1915. Serial No. 31,452.

To all whom it may concern:

Be it known that I, ALLEN E. J. LUCKHURST, a citizen of the United States, residing at Ridgewood, in the county of Bergen and State of New Jersey, have invented 5 a new and useful Flexible Boat-Launching Device, of which the following is a specification.

This invention relates to devices for 10 launching, and hoisting life boats on ships, and is designed as an improvement on the device filed by me in the Patent Office March 31, 1915, Serial No. 18297.

In my application referred to above, each 15 davit was operated by gearing on a fixed standard or support. In practice I have found that by so constructing my device all strains caused by the rolling, or pitching of the ship, are communicated to the gearing 20 in such a way as to bind the same against the easy operation of the davit and connecting apparatus.

It is the object of my present invention to 25 so construct the device that the operative gearing, both for the davits, and falls, will be inclosed against the weather, but will be so held that no strain will come upon the same except such as may be developed in the rotation of the davits, or the operation of 30 the falls.

The invention is illustrated in the accompanying drawings, in which —

Figure 1, is a side elevation of a portion of a ship with my improved flexible launching device applied thereto,—a part being in 35 section; Fig. 2, is a plan view, on an enlarged scale, of the operating mechanism, incased, for one of the davits, with a part of the casing broken away, and of the operating 40 mechanism for the falls; Fig. 3, is a side elevation of the mechanism shown in Fig. 2, looking longitudinally of the ship; Fig. 4, is a view of the same, looking outward toward the sea; and Fig. 5, is a sectional view showing 45 a detail of construction, taken on the line 5—5 of Fig. 2.

In the accompanying drawings, like numerals of reference refer to the same parts in each of the views.

50 In practice I provide a worm and worm gear to operate each davit, and a worm and two worm gears to operate each pair of drum ends for the falls.

As shown more particularly in Fig. 1, the 55 davits 6, are mounted on a ship, as 7, by

sockets, as 8, in each of which I preferably mount a ball bearing, as 9; and each davit is held firmly in place by a strap, as 10, which may be secured to the deck of a ship. The davit will thus be held firmly against 60 substantial movement either laterally, or longitudinally of the ship thereby leaving my improved flexible launching device entirely free from strain.

In making my improved flexible launching and hoisting device I provide a standard 11, on the top of which I flexibly mount a casing 12, which is normally free to swing laterally on the shaft 13, on the cylinder 14, and is free to swing rotatably on the shaft 70 15, mounted in the yoke 16, of the standard 11, whereby a substantially universal joint is formed which permits the casing 12, to move unhindered in any direction thereby relieving the inclosed gearing free from 75 strain from any movement of the davit and ship on which it is mounted. The davit 6, passes through the casing 12; and has mounted thereon a worm gear 17, within said casing, said worm gear being composed of 80 two parts, as shown more particularly in Fig. 5, secured together by bolts 18, whereby a continuous worm gear is formed with a hub 19, resting upon the surface 20, of the casing 12, and having an extension 21, fitting 85 within an annular collar 22, of the casing 12. The upper part of the worm gear is also preferably provided with a hub 23, and extension 24, fitting with the collar 25, of the casing 12. By having these extensions the worm gear, being composed of two parts, is held firmly together in addition to that embodied in the bolts 18.

In adapting the casing 12, for the reception of the worm gear 17, a semicircular portion 26, is provided to which the segmental portion 27, is secured by bolts 28, thereby providing a firm support for the worm gear, and also completely inclosing the gearing from the weather. The worm 29, is also 95 completely inclosed within the casing by the part 30, which is secured to the part 31, of the casing, by bolts 32. This worm is in mesh with the worm gear 17, as clearly shown in Fig. 2; and is operable by a crank 100 shaft 33, which passes inward beyond the casing, as shown so it can be easily engaged with a crank in the hands of an operator standing well within the zone of safety. The drum ends 34, and 35, are operable by 105

the worm 36, mounted on the crank shaft 37, which also extends athwart the ship and projects beyond the casing 12, so as to be easily engaged with a crank, as indicated by dotted lines in Fig. 3. Thus, both the shafts 33, and 37, can be operated from a zone of safety thereby removing liability of the operator being thrown into the sea by the rolling of the ship, or from other cause. 10 The drum end 34, is mounted on a shaft 38, carrying the worm gear 39, in mesh with the worm 36; and the drum end 35, is mounted on the shaft 40, carrying a worm gear 41, in mesh with the worm 36. Thus, by rotating the shaft 37, both drum ends will be rotated, as will be understood, and the life boat, as 42, can be either taken from the chocks 43, and launched, or can be hoisted from the sea and placed in the chocks, as 15 will be understood.

20 In operation, when it is desired to launch the life boat, the falls are operated by rotating each shaft 37, until the drum ends lift the boat from the chocks; first one davit and then the other is rotated by the respective shafts 33, in connection with the worms, and worm gears, until the boat is in a position without the vertical, longitudinal zone of the ship, as will be understood; when by again 25 rotating the drum ends the boat can be lowered to the sea. In hoisting the life boat from the sea, the operation is just reversed.

30 By having both sets of gearing in a flexibly-mounted support, there is absolutely no strain upon any of the gearing from the movement of the ship and davit, and, therefore, no possibility of binding, or increasing the friction. At the same time, the gearing is held in positive arrangement with the davit, 35 and with the falls and means for operating the same. By forming the worm gear 17, as shown, and mounting it as shown, I am able to mount my improved device on the davits of any ship, and operate the same in the most 40 desirable manner. By making both of the crank shafts 33, and 37, substantially parallel, and disposing them so they will project inwardly from the side of the ship, the boat is handled without any danger whatever of 45 any of the operators being thrown into the sea by any sudden movement of the ship, or from other causes. By making the casing, as shown and described, and bolting the portions thereon as described, I am not only able 50 to completely inclose the gearing from the weather, but am able to protect the life boat in its passage between the davits. The device is flexible, comparatively simple in construction, not expensive to manufacture, and is 55 very efficient in use.

60 I claim:

1. A flexible boat launching device comprising a pair of davits carrying falls, a worm gear and worm operatively connected with each davit, a worm and worm gears op-

eratively disposed relative to the falls on each davit, and a flexible support for both of said sets of gears.

2. A flexible boat launching device comprising a pair of davits and means to hold the same in fixed position relative to the ship, a worm gear mounted on each davit, a casing inclosing each worm gear, a worm mounted on a shaft in each casing, in mesh with the respective worm gear, a worm and worm gears mounted in each casing each of the latter carrying a drum end, a standard supporting said casing, and a double joint between said standard and casing whereby each casing is free to swing in two directions. 70

3. The combination with the davits of a ship, of gearing adapted to operate the davits, and gearing adapted to operate the falls, the operative shafts of both sets of gearing being substantially parallel and extending inwardly from the sides of the ship, a support for both sets of gearing, and a double joint between said support and said gearing whereby said gearing is free to swing in two directions. 80

4. The combination with the davits of a ship, of gearing adapted to rotate the davits, and gearing adapted to operate the falls, the operative shafts of both sets of gearing being substantially parallel, and extending inwardly from the sides of the ship, a casing in which both sets of gearing for each davit is mounted, a standard, and a double joint between said casing and said standard whereby said casing is free to swing in two directions. 95

5. The combination with the davits of a ship, of a worm gear composed of two parts mounted on each davit, a worm in mesh with each gear, a casing inclosing the worm and worm gear, said casing having two annular collars composed of segmental parts, and said worm gear having a hub on each side with extensions fitting within the respective collars, for the purpose set forth. 105

6. The combination with the davits of a ship, of a worm gear composed of two parts bolted on each davit, a worm in mesh with the worm gear on each davit, a casing inclosing each worm and worm gear, said casing having two annular collars composed of segmental parts and said worm gear having a hub on each side with extensions fitting within the respective collars, said casing being flexibly supported on the ship, for the purpose set forth. 115

7. The herein described flexible boat launching device comprising two davits pivotally mounted and secured on a ship, a worm gear fixed on each davit, a worm in mesh with each of said worm gears respectively, a casing inclosing said gears, worm and worm gears in each casing carrying drum ends, operative shafts mounted parallel in said casing and projecting from the inner end of the 120

same, said shafts carrying the respective worms, a standard, and a double joint connecting said standard with the respective casing whereby the casing is free to swing in two directions.

10
jacent said davit, and a revolute shaft having a bearing comprising a universal connection with said pillar and adapted to impart movement to said gear.

Dated this 29th day of May, 1915.

ALLEN E. J. LUCKHURST.
